HERBERT TROWBRIDGE WERREN, OF HAMPSTEAD, ENGLAND.

BALANCING TELEPHONE CABLES.

Application filed August 31, 1928, Serial No. 303,273, and in Great Britain June 16, 1927.

This invention relates to balancing telephone cables the object being to produce a telephone line with balanced sections, more particularly balanced loading sections, of 5 cable in an improved manner.

In order to balance telephone cables it has been proposed to divide a length of cable into two parts of approximately equal length, to make a crossing of the wires of each pair, and 10 to re-join them pair to pair respectively; in this way the unbalance of each pair in one of the said parts is substantially compensated by the inverse unbalance in the corresponding pair in the other of the said parts. Furthermore, 15 it has been proposed to reduce the disturbances between groups of adjacent conductors by first determining the differences in capacities of the conductors of one group in relation to those of another group and by 20 them adjusting the capacities of the groups, for example by making suitable crossings and joining the conductors of one group to those of another group, so that the capacities tend to balance. But in the known methods of 25 balancing telephone cables, the balancing of a given loading section consisting of a number of jointed cable lengths of a multiple twin cable is accomplished at joints between adjacent cable lengths, by crossing the conductors 30 of quads selected solely on account of the magnitude of their "capacity unbalances."

In the manufacture of lengths of cable each comprising a plurality of quads, the different quads are provided with means by which they 35 may be identified; for example, different quads may be differently coloured, or may carry numerals or other symbols at their ends by which they can be identified. It is obviously convenient, if, when successive cable lengths

are joined together, a red quad (for example) 40 in one length is connected to a red quad in the neighbouring length, a green quad to a green quad, and so on. Similarly, where the quads bear numerals such as I, II, and so on, it is 45 convenient for quad I in the first length to be connected to quad I in the second length, for quad II in the first length to be connected to quad II in the second length, and so on. Where the quads are connected in this way, so 5 that to each quad are joined quads of the same colour, or quads bearing the same symbols, the "colour scheme", or the "identity of the quads", is said to be maintained throughout the cable. Where, however, the crossings 5 of the conductors of quads are selected solely on account of the magnitudes of the "capacity unbalances", the colour scheme or the identity of the quads is not maintained throughout the cable.

Furthermore, the method of cable balancing referred to above has additional disadvantages. For example, the 2-pair quads of a cable in which "four-wire" working is desired must be divided into at least three groups for balancing, this reduces the number 60 of quads in each balancing group and also makes it necessary to design in advance the complete transmission system comprising the four-wire and two-wire circuits required.

In the methods used heretofore, in which 70 the cross-talk between quads is reduced by mixing its ultimate value is always indeterminate, and depends upon the number of quads in the balancing group. In the case of large cables containing large balancing 75 groups these values may be within permissible limits, but in the case of small cables or cables containing small balancing groups

there are not sufficient possibilities of eliminating the unbalances and therefore the cross-talk may exceed permissible limits. Moreover a cable comprising only a small number of quads cannot be used for four-wire working. Another disadvantage of this known system of balancing is that as the resulting run of any individual quad throughout the finished cable section is not predetermined, difficulties may arise in subsequent repair work. The object of this invention is to overcome these disadvantages, by so arranging a cable section that quads in adjacent cable lengths are joined together in a predetermined manner (for example, to maintain the identity of the quads or to maintain the colour scheme throughout the section); quads from different cable-lengths which are ultimately to be joined together to give a predetermined run will, for brevity, be referred to as "similar quads".

In the method of balancing a section of a telephone (or telegraph) cable (for example a loading section) according to this invention the capacity-unbalances both within quads and between quads are first measured in each of the lengths of cable which are ultimately to constitute a cable section, a determination is then made from these unbalances of the crossings between the conductors of each 2-pair quad at each of the successive joints, similar quads being joined together throughout the section, which are required to produce the minimum residual unbalance, all crossings being made within quads, whereupon the cable lengths are jointed with the appropriate crossings to form a section which is substantially a balanced cable section. The individual quads are joined in a predetermined order; for example, the quads are joined to maintain their colour identity throughout the cable section.

As another example, the predetermined order might be such that, considering any pair of quads, in two consecutive cable lengths which are joined together, the quads adjacent to one of the said pair of quads in the first of the said consecutive cable lengths, are connected to the quads adjacent to the other of the said pair of quads in the second of the said consecutive cable lengths. In cables in which the quads are connected in this manner, the same relative spacing of the quads may be said to be preserved throughout the cable section, since, considering any selected pair of circuits in the cable, the mutual distances between the conductors forming the said pair of circuits will be the same in every cable length in the section. Quads spaced in this way will also hereinafter be referred to as

being "uniformly spaced" throughout the cable. In the form of cable known hitherto, however, a pair of circuits, which were neighbours in one cable length, might well be widely spaced in a subsequent cable length, so that the mutual distances between the conductors forming the pair would vary greatly.

That is to say any individual quad in a cable length is connected with the similar quad in the most appropriate cable length (not necessarily adjacent) by a suitable arrangement of the crossings of the wires at the joints between the intermediate cable lengths. The method is preferably applied without the use of auxiliary balancing condensers, but if desired these may be used in conjunction with the method described.

In practice the method of balancing according to the invention may be carried into effect in the following manner. The capacity unbalances of the 2-pair quads both within the quads and between adjacent quads are determined in each of the lengths of cable of which for example there may be eight which are ultimately to constitute the cable section. These values for any given quad (for example quad No. 1), are then scheduled in the order of the magnitude for the most important circuit with the corresponding numbers of the cable lengths, eight in all. For example it may happen that the capacity unbalances, for example, between a phantom and a side circuit, in decreasing order of magnitude show that the lengths of the quad to be connected to obtain a progressive reduction of the capacity unbalance along the lengths should be connected in the order 1, 5, 7, 4, 2 and so on instead of 1, 2, 3, 4, 5 and so on. But in practice the cable lengths will be laid in the order 1, 2, 3, 4 and so on, so that the joints of any quad must actually be made between lengths 1 and 2, 2 and 3, and so on. In order to accomplish this and eliminate the capacity unbalances it is therefore necessary to find the crossings required. Accordingly from the schedule (for example for quad No. 1), of capacity-unbalances in numerical order of magnitude is compiled a second schedule with the numbers of the lengths in irregular sequence and the conventional references A B C D identifying the individual wires of a quad are inserted for each item and are arranged to show the crossings required between the quad lengths numbered and arranged in irregular sequence together with the calculated residual unbalances as successive lengths are joined together.

When this schedule is thus completed it is then possible to determine by inspection the actual crossings required in practice between

the conductors of this quad at each of the joints between consecutive lengths, (that is to say in regular sequence) to eliminate the capacity unbalances within this quad.

5 So far only the capacity unbalances within a quad have been considered. These capacity unbalances in the case of a 2-pair quad arranged with two two-wire side circuits and a phantom circuit, as is known, usually comprise 10 five quantities conventionally designated in the art as follows:—Side 1 to side 2, phantom to side 1, phantom to side 2, side 1 to earth, and side 2 to earth. But there are also capacity unbalances between laterally adjacent 15 quads which for accurate balancing of a cable section must be considered. For example the capacity unbalances between two such adjacent 2-pair quads (quad No. 1 and quad No. 2) as is known, usually comprise 20 nine quantities conventionally designated in the art as follows:—

Phantom 1 to phantom 2, phantom 1 to pair 3, phantom 1 to pair 4, phantom 2 to pair 1, phantom 2 to pair 2, pair 1 to pair 3, 25 pair 1 to pair 4, pair 2 to pair 3, pair 2 to pair 4. Now in accordance with the invention after the values of the capacity unbalances within quads, for example to take two quads (quad No. 1 and quad No. 2) have 30 been set out in the form of schedules, and the required crossings for one quad (quad No. 1) have been determined, a second schedule is made of the capacity unbalances between the two quads (quad No. 1 and quad No. 2) and 35 of the capacity unbalances within the second quad. From this schedule a final determination of the crossings at the successive joints in the second quad (quad No. 2) is made to compensate for both the capacity unbalances 40 within that quad and also the capacity unbalances between the two adjacent quads. With quads jointed in this manner each section of the cable will be substantially a balanced section. The crossings for quad 45 No. 3 are determined in a similar manner taking into consideration the capacity unbalances between quad No. 2 and quad No. 3, and the capacity unbalances within quad No. 3. The remaining quads are dealt with 50 similarly.

A method according to the invention will now be described with reference to numerical examples and the accompanying diagrammatic drawing in which Fig. 1 is intended to 55 illustrate a loading section of a cable made up of eight standard lengths of cable, only two 2-pair quads being shown. Fig. 1 shows the connections between the first five lengths

only and Figure 2 shows conventionally, in the usual way a diagram of the network of effective capacities by which cross-talk is produced.

The lengths of cable are indicated by numbers 1, 2, 3, to 8. The capacity unbalances within quad No. 1, within quad No. 2, and between the quads are measured for each of the lengths numbered 1 to 8, and are then set out in schedules. The within-quad unbalances for quad No. 1 are then arranged in decreasing order of magnitude (irrespective 70 of sign) for the phantom to side circuits. It may however, be convenient to depart slightly from this arrangement if any of the unbalances are abnormally large, as described below. The within-quad unbalances for 75 quad No. 2 are arranged in a similar manner. The between-quad unbalances for the two quads are left in the numerical order of the lengths.

These three schedules are shown below:— 80

SCHEDULE A.

Quad No. 1 within-quad unbalances—mmF.

Length No.	S ₁ -S ₂	PH-S ₁	PH-S ₂	S ₁ -E	S ₂ -E	85
1	-5	-58	+28	+44	+31	
4	+26	+25	-5	-44	-29	
2	-18	+23	+3	-17	-5	
6	-9	-22	-8	-6	-22	
7	-20	+22	+6	-33	+27	
5	+30	-10	-17	+21	+12	90
8	-13	+8	+5	+8	-15	
3	+7	+6	-2	-45	-12	

SCHEDULE B.

Quad No. 2 within-quad unbalances—mmF.

Length No.	S ₁ -S ₂	PH-S ₁	PH-S ₂	S ₁ -E	S ₂ -E	95
2	+2	-15	+55	+60	+8	
4	-21	+40	+45	+20	+35	
3	-18	-18	+45	+51	+72	
1	-18	+41	-8	+54	+49	
5	+36	+12	+35	+98	-20	
7	+17	+22	+27	+22	-23	
6	-12	-30	+12	-10	+3	
8	+12	+25	-2	+33	+30	105

SCHEDULE C.

Length No.	PH ₁ - PH ₂	PH ₁ - Pr ₃	PH ₁ - Pr ₄	PH ₂ - Pr ₁	PH ₂ - Pr ₂	Pr ₁ - Pr ₃	Pr ₁ - Pr ₄	Pr ₂ - Pr ₃	Pr ₂ - Pr ₄	110
1	+6	-45	-10	-10	+15	+15	+29	-12	-36	
2	-18	+12	+4	-10	-8	+17	+25	+20	-3	
3	+23	+35	-4	-5	-21	-8	0	-32	-49	
4	-5	+8	+30	+29	-2	+48	-5	-25	-20	
5	+3	+7	-20	+24	-13	-5	-8	-33	-49	
6	-2	+2	-38	-17	-21	-30	0	-30	-20	
7	+28	+5	+36	+14	-8	+13	+15	-15	+1	115
8	+6	-9	-15	+2	-8	+5	-6	+2	-31	

It will be seen that the within-quad unbalances shown in Schedules A and B have been arranged principally in the order of magnitude of the unbalances of the phantom-side circuits, but that this arrangement has been slightly departed from, as referred to above, in the case of Schedule B. In the case of Schedule A the magnitudes of the unbalances run as follows: 58, 25, 23, 22, 22, (all 10 in PH-S₁), 17 (PH-S₂), 8, 6, (both in PH-S₁). In the case of Schedule B, the order is preserved for lengths Nos. 2-5: thus— 55, 45, 45, (all in PH-S₂), 41 (in PH-S₁), 35, (in PH-S₂); but length No 5 is followed 15 by length No 7, despite the fact that the larger phantom-side unbalance in length No. 6 (namely, 30 mmF.) is greater than the larger phantom-side unbalance in length No. 7 (namely, 27 mmF.), because the difference 20 between the two is small and the remaining unbalances in length No. 7 (namely, 17, 22, 22, 23, mmF.) are considerably greater than the remaining unbalances in length No. 6 (namely, 12, 12, 10, 3 mmF.) The remaining length of Schedule B will be seen to follow in the order prescribed.

Now examining first the schedule for quad No. 1 and determining the required crossings, 30 which are indicated by rearranging the order of the conventional references A B C D, we arrive at a selection of connection for quad No. 1, as shown in the following schedule,

which also shows the reduced magnitude of the residual unbalances:—

35

SCHEDULE D.

Quad No. 1.

The capacity unbalances within quad No. 2 and between quads Nos. 1 and 2 are now arranged in the order shown in Schedule B, and the appropriate crossings determined for quad No. 2 by inspection and calculation as well known in the art so as to reduce at the same time both the within-quad unbalances for quad No. 2, and the unbalances between the two quads. In this way we obtain Schedule E as follows the crossings for quad No. 1 being obtained from Schedule D:—

SCHEDULE E

Length No.	Quad No. 1	Quad No. 2	Within quad unbalances quad No. 2					Between quad unbalances quad 1—quad 2								
			S-S	PH-S ₁	PH-S ₂	S-E ₁	S-E ₂	PH ₁ - PH ₂	PH ₁ - Pr ₃	PH ₁ - Pr ₄	PH ₂ - Pr ₁	PH ₂ - Pr ₂	Pr ₁ - Pr ₃	Pr ₁ - Pr ₄	Pr ₂ - Pr ₃	Pr ₂ - Pr ₄

75

The arrangement of the conventional references A B C D for both quads is shown in Schedule E which gives the final selection of the connections for the two quads which have been considered.

The lengths of cable may now be jointed, the necessary crossing between the conductors

at the successive joints along the respective core being made by reference to the arrangement of the A B C D groups for each of the lengths as shown in the final schedule given above. The drawing shows the crossings for the first five cable lengths only.

It will be understood that the same method

80

is applicable to the remaining 2-pair quads in the cable, the capacity unbalances within each quad and between adjacent quads being measured and the results scheduled and arranged to give the crossing required.

Where auxiliary balancing condensers are employed, the values of these are determined in the ordinary way after the jointing of the cable lengths has been performed. Consider, 10 for example, quad No. 2. The effective capacities between the several wires A, B, C, D and ground, and the effective mutual capacities between the pairs of wires are represented by the condensers a, b, c, d and $w, x, 15 y, z$, as shown in Figure 2. The unbalances referred to, in the schedules given above, under the headings S_1-S_2 , $PH-S_1$, $PH-S_2$, S_1-E and S_2-E are given by the following expressions, respectively, in terms of these effective 20 capacities:

$$\begin{aligned} S_1-S_2 &= w-x-z+y \\ PH-S_1 &= w-x+z-y \\ PH-S_2 &= w-z+x-y \\ S_1-E &= a-b \\ S_2-E &= c-d \end{aligned}$$

25 The residual values of these unbalances are, from Schedule E,

$$\begin{aligned} S_1-S_2 &= w-x-z+y=4 \\ PH-S_1 &= w-x+z-y=-16 \\ PH-S_2 &= w-z+x-y=4 \\ S-E_1 &= a-b=5. \\ S-E_2 &= c-d=105. \end{aligned}$$

From the last two equations it appears that if a condenser b^1 of capacity 5 mmF. be connected between wire B and ground, as shown in Figure 1, and if a condenser d^1 of capacity 105 mmF. be connected between wire D and ground, the unbalances S_1-E , and S_2-E will be reduced to zero. Similarly, if a 35 condenser w^1 of capacity 6 mmF. is connected between wire A and wire C, and a condenser z^1 of capacity 10 mmF. is connected between wire A and wire D, it will be seen that the 40 unbalances given by the remainder of the expressions above will be reduced to zero. The procedure outlined does not differ in principle from that commonly used in balancing by means of condensers, and it is thought that the forgoing example will make 45 the matter clear to those skilled in this art.

50 Moreover, it will be understood that the method according to the invention may be applied by first balancing parts of a cable section, for example by groups of 4 lengths, 55 connecting the lengths in each group with appropriate crossings and then balancing the groups and connecting them with appropriate crossings to obtain a substantially balanced section whilst maintaining the identity 60 of the quads throughout the cable section. The capacity unbalances for the groups may be determined if desired in the field.

One advantage of the method according to the invention is that it enables a telephone

system to be designed for long distance working where four-wire repeater working is essential, with a relatively small number of circuits, as quads suitably placed apart throughout the length of the line can be readily chosen. Another advantage is that 65 cross-talk between quads can be reduced considerably below the values which are normally obtained by mixing the quads as in the prior art on account of the fact that similar quads are adjacent through the whole cable, 70 thus enabling the cross-talk between these quads to be reduced by measurement of the unbalance and suitable crossings of the wires or pairs.

It is to be understood that the method according to the invention may be applied in a similar manner to a non-phantommed cable.

The method according to the invention can be applied in conjunction with the present known methods of balancing, for example in 85 a cable having a centre, first and second layers, the centre and first layers may be balanced by "mixing" and the circuits used for two wire working, whilst the second layer may be balanced in accordance with the invention and the circuits used for four wire working.

I claim:

1. A method of balancing a section of an electric signalling cable comprising a plurality of 2-pair quads divided into lengths, according to which the capacity unbalance within and between quads are first measured in each of the lengths of cable which are ultimately joined to constitute a cable section, a 95 determination is then made from these unbalances of the crossings in or between pairs of conductors at each successive joint, conductors being joined together throughout the section which are required to produce the minimum residual unbalances, whereupon the cable lengths are jointed with the appropriate crossings to form a section which is substantially a balanced cable section.

2. A method of balancing a section of an 100 electric signalling cable comprising a plurality of 2-pair quads divided into lengths, according to which the capacity unbalances both within the quads and between adjacent quads are first measured for each of the 105 lengths of cable which are ultimately joined to constitute a cable section, and a determination is then made from these measurements of the crossings between the conductors of each 2-pair quad at each successive joint, 110 similar quads being jointed together throughout the section, which are required to produce the minimum residual unbalances, whereupon the cable lengths are jointed with the appropriate crossings to form a section which is 115 substantially a balanced cable section.

3. A method of balancing a section of an 120 electric signalling cable, comprising a plu-

rality of 2-pair quads divided into lengths, according to which the capacity unbalances both within the quads and between adjacent quads are first measured for each of the 5 lengths of cable which are ultimately joined to constitute a cable section, the appropriate crossings for individually balancing the quads and the appropriate crossings between the said groups of conductors are determined 10 from said measured unbalances and the joints made, the same relative spacing of the quads being maintained throughout the whole cable section.

4. A method of balancing a section of an 15 electrical signalling cable, comprising a plurality of 2-pair quads divided into lengths which are afterward joined, according to which the capacity unbalances both within the quads and between adjacent quads are 20 first measured for each of the lengths of cable which are ultimately joined to constitute a cable section and, as determined from said measured unbalances, a selection of crossings is made at some of the joints for 25 the unbalances between quads, and a selection of crossings is made at the remaining joints

for the unbalances within quads substantially as described, the crossings being made within quads.

5. A method of balancing a section of an 30 electric signalling cable, comprising a plurality of 2-pair quads divided into lengths which are afterward joined, according to which the capacity unbalances both within the quads and between adjacent quads are 35 first measured for each of the lengths of cable which are ultimately joined to constitute a cable section and, as determined from said measured unbalances, a selection of crossings is made at some of the joints for the unbalances within quads, and a selection of crossings is made at the remaining joints for the unbalances both within and between quads, substantially as described, the crossings being 40 made within quads.

6. A method of balancing a section of an 45 electric signalling cable according to claim 2, wherein the capacity unbalances between the circuits are further reduced by the insertion of auxiliary balancing condensers.

HERBERT TROWBRIDGE WERREN.
